UNITED STATES PATENT OFFICE.

GEORGE E. SHAW, OF PUTNAM, CONNECTICUT.

DESIGN FOR A SPOON.

SPECIFICATION forming part of Design No. 21,058, dated September 22, 1891.

Application filed July 2, 1891. Serial No. 398,304. Term of patent 3½ years.

To all whom it may concern:

Be it known that I, GEORGE E. SHAW, of Putnam, in the county of Windham and State of Connecticut, have invented and produced 5 a new and original Design for Spoons, of which the following is a specification, reference being had to the accompanying drawing, forming part thereof.

The essential features of my design are a 10 representation of a Queen's-arm gun extending along the shank of the handle, a representation of the head of General Putnam, and a representation of the head of the wolf, the two latter features occupying positions upon 15 the broader portion of the handle.

A represents the bowl of the spoon, B the

wider portion of the handle, and b the narrow or shank portion of the handle.

C represents the Queen's-arm gun extending along the narrow portion of the handle. 20

D represents the head of General Putnam, having a cocked hat thereon, and E represents the head of the wolf. There is also represented upon the handle a powder-horn F and oak-leaves G.

25

What I claim is—

The design for a spoon, as herein shown and described.

GEORGE E. SHAW.
